UNITED STATES PATENT OFFICE

147,772

DESIGN FOR A UNIT COMBINATION DINING TABLE AND CHAIRS

Tollie L. Williamson and Henry A. Nettles, Little Rock, Ark.; said Nettles assignor to said Williamson

Application May 13, 1946, Serial No. 129,652

Term of patent 14 years

(Cl. D33—14)

To all whom it may concern:

Be it known that we, Tollie L. Williamson and Henry A. Nettles, residing at Little Rock, in the county of Pulaski and State of Arkansas, have invented a new, original, and ornamental Design for a Unit Combination Dining Table and Chairs, of which the following is a specification, reference being had to the accompanying drawing, forming part thereof.

We claim:

The ornamental design for a unit combination dining table and chairs, substantially as shown.

TOLLIE L. WILLIAMSON.
HENRY A. NETTLES.
